United States Patent Office

Des. 202,648
Patented Oct. 26, 1965

202,648

LIGHTING FIXTURE

Carl X. Meyer, St. Louis, and Willard R. Garnett, Bellefontaine Neighbors, Mo., assignors to Emerson Electric Co., a corporation of Missouri

Continuation of design applications Ser. Nos. 72,946 and 72,947, Dec. 26, 1962. This application Sept. 21, 1964, Ser. No. 81,820

Term of patent 14 years

(Cl. D48—23)

FIG. 3

FIG. 1

FIG. 2

FIG. 1 is a perspective view as seen from below of a lighting fixture showing our design;

FIG. 2 is a perspective view taken from above the lighting fixture, the opposite end not shown being substantially the same;

FIG. 3 is a transverse sectional view taken at line 3-3 in FIG. 2;

FIG. 4 is a perspective view as seen from below of a lighting fixture showing a modification of our design;

FIG. 5 is a perspective view taken from above of the lighting fixture seen in FIG. 4, the opposite end not shown being substantially the same; and

FIG. 6 is a transverse sectional view taken at line 6-6 in FIG. 5.

This application is a continuation of our co-pending

applications Serial Nos. D-72,946 and D-72,947, both filed June 26, 1962 and both now abandoned.

We claim:

The ornamental design for a lighting fixture, substantially as shown and described.
